CLAIM

The ornamental design for a radiography and fluoroscopy system, as shown and described.

DESCRIPTION

FIG. 1 is a front elevation view of the radiography and fluoroscopy system showing my new invention;

FIG. 2 is a rear elevation view thereof;

FIG. 3 is a top plan view thereof;

FIG. 4 is a bottom plan view thereof;

FIG. 5 is a right elevation view thereof;

FIG. 6 is a left elevation view thereof; and,

FIG. 7 is a perspective view thereof.

The broken lines immediately adjacent the claimed areas represent the bounds of the claim, and all other broken lines are directed to portions of the radiography and fluoroscopy system that form no part of the claimed design. None of the broken lines form a part of the claimed design.
